United States Patent

Des. 237,476
Patented Nov. 4, 1975

237,476

UTILITY TRUCK

William L. Figura, R.F.D. 2, Bruce, Wis. 54819

Filed Sept. 18, 1974, Ser. No. 506,976

Term of patent 14 years

Int Cl. D12—08

U.S. Cl. D12—85

FIG. 3

FIG. 4

FIG. 1 is a perspective view of the front and one side of a utility truck showing my new design, it being understood that the side opposite to that shown herein is a mirror image thereof;

FIG. 2 is a top plan view thereof;

FIG. 3 is a rear perspective view thereof; and

FIG. 4 is a front perspective view thereof.

I claim:

The ornamental design for a utility truck, substantially as shown.
